UNITED STATES PATENT OFFICE.

ALFRED H. HANSON, OF CHICAGO, ILLINOIS.

BRUSH.

Application filed August 6, 1924. Serial No. 730,474.

To all whom it may concern:

Be it known that I, ALFRED H. HANSON, a citizen of the United States, residing at 4121 W. Lake St., Chicago, in the county of

5 Cook and State of Illinois, have invented new and useful Improvements in Brushes, of which the following is a specification.

This invention relates to new and useful 10 improvements in brushes and more particularly to a type of brush which is particularly adapted for use in cleaning automobiles and the like. The main object of my invention is the provision of a brush adapted to be used with or without a novel 15 spray apparatus whereby the brushes may be utilized for cleansing motor vehicles, busses and the like.

Another object of my invention is the provision of a brush having novel means for 20 detachably connecting the brush to a spray nozzle whereby the water or cleansing fluid issuing from the mouth of the nozzle will be readily conveyed to the brush and absorbed thereby for use in cleansing pur- 25 poses.

With the above and other objects in view, the invention consists in the novel features 30 of construction, the combination and arrangement of parts hereinafter more fully set forth, pointed out in the claim and shown in the accompanying drawings, in which:

Fig. 1 is a plan view of a brush constructed in accordance with my invention,

35 Fig. 2 is a similar view on a smaller scale illustrating the brush member detached from the spray nozzle,

Fig. 3 is a transverse section on the line 3-3 of Fig. 1,

40 Fig. 4 is a detail longitudinal section through the mouth of the spray nozzle and

Fig. 5 is a transverse section on the line 5-5 of Fig. 1.

45 In carrying out my invention I provide a brush member 1 which may be of any form desired and properly constructed of two pieces of wire twisted together as shown at 2 with the bristles 3 of the brush engaged between the twisted strands of the wire.

50 The ends of the twisted strands are arranged parallel in the present instance as

shown at 4 and disposed within a U-shaped clamping plate 5 which is attached to the nozzle 6 by means of a bolt 7 passing through the nozzle and a wing nut 8 upon its threaded end for moving the plate 5 into clamping engagement with the ends of the twisted strands so that the ends of the twisted strands will be securely clamped between the plate and the bristle surface of the nozzle 6.

The clamping action obtained by the construction set forth above is clearly illustrated in Fig. 3 where it will be noted that the ends of the twisted strands of wire are disposed in the corners of the U-shaped clamping plate and positioned directly against the outer surface of the nozzle 6, the wing nut 8 retaining the plate 5 in clamping position to securely hold the ends of the brush in place.

In the outer end of the nozzle member 6 a sleeve 9 is arranged having an opening 10 therethrough of a smaller diameter than the main portion of the nozzle and attention is hereby directed to the fact that the bolt 7 extends transversely across this reduced opening 10 and forms restricted outlets 11 upon each side of bolt 7 so that water passing through the nozzle under pressure will be sprayed as it passes out of the sleeve 9 thoroughly saturating the brush with the cleansing fluid so that it may be readily applied to the parts being cleansed.

The nozzle 6 may be attached to a hose 85 line 12 by means of a coupling 13 or any other suitable manner.

While in the above description I have set forth a particular type of brush, I wish it to be understood that various types of brushes may be used with the ends of the strands clamped to the nozzle by means of the clamping plate 5. It will be apparent that the brushes may be quickly and readily pressed in position and securely clamped against movement through the adjustment of the wing nut 8 or they may be quickly and readily removed when it is desired to change the character of the brush.

While I have shown and described the 100 preferred embodiment of my invention, it will be understood that various changes and

alterations may be made without departing from the spirit of the invention or the scope of the appended claim.

Having thus described my invention,
what I claim is:

A device of the character described including a brush member, a nozzle, a bolt extending transversely through the nozzle at the outer end thereof, a U-shaped clamping

plate mounted upon the bolt and adjustable ¹⁰ means on the bolt whereby said plate may be moved toward and away from the nozzle for clamping the brush in position with respect to the outer end of the nozzle.

In testimony whereof I affix my signature.

ALFRED H. HANSON.
